Inventor:
Harry D. Binks
by Albert Scheibb, atty.

UNITED STATES PATENT OFFICE.

HARRY D. BINKS, OF RIVER FOREST, ILLINOIS.

SPRAY TANK.

Application filed June 26, 1922. Serial No. 571,051.

To all whom it may concern:

Be it known that I, HARRY D. BINKS, citizen of the United States, residing at River Forest, in the county of Cook and State of Illinois, have invented certain new and useful Improvements in a Spray Tank; and I do hereby declare the following to be a full, clear, and exact description of the invention, such as will enable others skilled in the art to which it appertains to make and use the same.

My invention relates to liquid material tanks of the general class commonly employed in connection with the spraying of paints, namely tanks arranged for having liquids forced out of the same by means of compressed air. Generally speaking, my invention aims to provide an inexpensive, easily manipulated and highly efficient arrangement for this purpose in which the needed adjusting, gaging and safety provisions are all carried by the head of the tank; in which this head can easily be attached to or detached from the container; in which the liquid is forced out of the same through passages which are not likely to clog, and in which a proper sealing of the joint between the head and the container portion of the tank is easily effected.

In employing compressed air for forcing a liquid such as paint out of a tank, it is important that adequate provisions should be made for agitating the liquid to secure a substantially uniform consistency, that the issuing liquid should be duly strained to prevent its clogging the passages through which it is forced, that the pressure existing within the tank should be known at all times and easily be controlled, and that adequate safety provisions should be made for preventing the applying of an excessive pressure to the tank by an inexperienced or careless operator.

My invention aims to provide a spray tank arranged to meet all of these requirements and one in which the various provisions just mentioned are all carried by the head of the tank and removable with the same, so as to facilitate both the replenishing of the liquid in the tank and the thorough cleaning of the latter. Furthermore, my invention aims to accomplish these various objects in an unusually simple and rugged construction and one which will permit even an inexperienced operator to make all needed

adjustments without difficulty. It also aims to provide an advantageously constructed valve body for such an appliance. Still further and also more detailed objects will appear from the following specification and from the accompanying drawings, in which—

Fig. 1 is a fragmentary and enlarged view of a spray tank embodying my invention, with the major portion of the head and a part of the lower portion of the container, as well as one of the wheels and the foot of the tank in elevation, and with the other parts in the central and vertical section.

Fig. 2 is an enlarged vertical section taken along the correspondingly numbered line in Fig. 1 through the valve body and the adjacent portion of the head.

Fig. 3 is a horizontal section taken through the valve body along the line 3—3 of Fig. 2, with the means for controlling the diaphragm valve attached.

Fig. 4 is a vertical section taken along the line 4—4 of Fig. 2.

Fig. 5 is a perspective view of the nipple which affords the guide and seat for the movable member of the adjustable valve.

Fig. 6 is a plan view of the valve body and its fittings.

In the embodiment of the drawings, the container portion of my tank is desirably mounted on a pair of wheels 1 after the usual manner, with a foot 2 arranged as the third support, and the tank proper has a main container portion comprising a frustoconical casing 3 welded to a rounded bottom 4, which bottom is preferably cupshaped so as to have a rounded interior which will facilitate cleaning. Brazed or welded to the top of the casing 3 of the container is a ring casting 44 which desirably extends upwardly beyond the casing 3 to afford protection for the mouth of the container, and this mouth portion of the casting has an upwardly open groove for receiving a packing ring 5. Seated on this packing ring with its outer edge is a head casting 6, which casting desirably is of an inverted cup shape and desirably has an upwardly directed ring 7 on it to afford a flat seat for a valve body 8. This valve body is clamped to the head 6 by a screw 9 and by a pair of nipples 10 and 11 which respectively form portions of the passages for supplying compressed air to the tank and for the discharge of the paint or other liquid.

To clamp the head tightly to the container proper, I provide the head with cam means which are adapted to interlock with suitable formations on the mouth ring 4 and which are adjustable so as to compensate both for any irregularities in the shape of the parts and for effective differences in the thickness of the packing ring 5, as more fully described in my divisional application No. 10 714,524, filed May 19, 1924, on a pressure tank.

Within the casing, the nipple 11 is connected by a coupling 24 to an agitator pipe 25 which extends almost to the bottom 4 of 15 the container and which desirably has its lower end coiled around the lower end of a casing 26 containing a strainer 27. The coiled lower end of the agitator 25 is provided with openings 28 directed towards the 20 bottom of the casing, so that the compressed air issuing through this pipe will stir up any sediment in the liquid or any heavy portions in the same, thereby insuring a thorough intermingling of the different 25 portions of the liquid which is to be forced out of the tank. The coupling 24 also desirably houses a check valve 29 arranged (as shown for example in Fig. 4) so as to be opened by the pressure of the downwardly passing air 30 and so as to be closed by upward pressure through the agitator pipe to prevent liquid from being forced into the air supply passages of my appliance.

The strainer casing 26 is desirably carried by a paint outlet pipe 30 which is threaded to the nipple 10, this nipple in turn being threaded into the valve body 8 in alinement with a bore 31 which leads to a lateral bore 32 into which the paint outlet 40 nozzle 33 is threaded. By thus making a direct connection as shown in Fig. 2, I reduce the passages through which the liquid must pass in issuing through the valve body, thereby likewise reducing the chances of 45 clogging.

The nipple 11 through which the air supply pipe or agitator pipe 25 is connected, is threaded into the valve body 8 in alinement with a vertical bore 63 which leads to the 50 inner end of a lateral bore 34 into which the usual relief valve 35 (here shown as a pop safety valve) is threaded. The inner end of the lateral bore 34 is also connected by a port 36 with a chamber 37 in one end of the 55 valve body and this chamber is connected by a partly threaded bore 38 with a bore 39 extending transversely thereof through the valve body and having its opposite end portions 40 and 41 respectively threaded for receiving an air inlet cock 60 and an air outlet cock 61.

Threaded into the longitudinal bore 38 adjacent to the chamber 37 is a regulator valve body 42 which has a valve stem 43 65 slidably mounted in it, this stem having a

head adapted to seat on the inner end of the regulator valve body and being continuously urged towards such seating by a spring 64 interposed between the valve stem and a thrust member 45 which is also threaded 70 into the bore 38. Thus arranged, it will be obvious from Fig. 5 that the spring 64 will continuously tend to seat the valve stem so as to shut off the passing of air from the chamber 37 through grooves 65 alongside 75 the stem of the valve and through the bore of the thrust member 45 to the air outlet 41.

To effect the desired air connection through the passages just mentioned, I provide means which can be adjusted from the 80 exterior of the valve body and for that purpose desirably employ a diaphragm 46 bearing against the outer end of the valve stem 43 and continuously urged against this diaphragm by a compression spring 47 interposed between the diaphragm and the thumb screw 48, the latter screw being threaded through a cap 49 which in turn is threaded into the outer end of the chamber 37 after the manner shown in Fig. 5. When the screw 90 48 is turned backward (or loosened to the extent shown in Fig. 5) so as to relieve the pressure of the spring 47, the relatively lighter spring 44 seats the valve and shuts off the air connection from the air inlet 40 95 to the duct 63 which leads to the agitator pipe. Upon tightening the screw 48, the spring 47 is compressed, thereby flexing the diaphragm inwardly and opening the valve 100 adjacent to the same, thereby admitting air 100 to the agitator to any desired extent.

To insure a proper control of the pressure by the operator, I desirably provide a pressure gage 50 threaded into the bore 32^a which leads to an extension 51^a of the bore 105 51 into which the screw 9 is threaded, this extension bore 51^a being continued upwardly to meet the bore 51 which extends longitudinally of the valve body to the chamber 37.

With the parts thus arranged, the bore 39 110 affords a direct connection from the air inlet to the air outlet of the appliance, thus permitting the compressed air to be supplied without any throttling action to the appliance with which the spray tank is to be 115 used, while the pressure at which air is supplied through the agitator pipe to the container can be varied as desired by manipulating the thumb screw 38 and can always be judged instantly from a reading 120 of the gage 50. Moreover, by suitably adjusting the relief valve 35, I can readily limit the pressure at which the compressed air is supplied to the tank. My compact mounting for the various parts therefore enables 125 me to accomplish all of the needed purposes by means of a very simple and cheaply constructed valve head.

However, while I have illustrated and described the appliance of my invention as 130

including highly desirable shapes and types of various parts, I do not wish to be limited to the details of the construction and arrangement thus disclosed, it being obvious that the same might be modified in many ways without departing either from the spirit of my invention or from the appended claims.

I claim as my invention:—

10 1. A liquid spray tank comprising a container, a cover secured to the mouth thereof, a valve body seated on the cover and having bores one of which leads to a gauge connection, an agitator duct and a liquid outlet duct both extending through the cover and threaded into the valve body, and a screw extending through the cover and threaded into the said one bore, the said screw cooperating with the said ducts in 20 clamping the valve body to the cover.

2. A liquid spray tank having a valve body secured to the cover thereof and connected to the interior of the tank by an agitator duct and a liquid outlet, an air supply bore extending transversely through the valve body and intercepted by a bore extending longitudinally of the body and connected to the agitator duct, and an adjustable valve controlling the said intercept- 30

3. A spray tank as per claim 2, in which the valve comprises a perforated stop member and a nipple both threaded into the said longitudinal bore, a valve member 35 slidable in the nipple and having a head adapted to seat on the nipple, a spring interposed between the stop member and the valve member, and an adjustable spring re-

sisting the movement of the valve member by the aforesaid spring. 40

4. A spray tank as per claim 2, in which the valve comprises a perforated stop member and a nipple both threaded into the said longitudinal bore, a valve member slidable in the nipple and having a head adapted to 45 seat on the nipple, a spring interposed between the stop member and the valve member, a diaphragm bearing against the valve member and having its faces respectively subject to external air pressure and to the 50 pressure within the said intercepting bore, and spring means engaging the diaphragm on the opposite side from the valve member for resisting a movement of the valve member by the aforesaid spring. 55

5. A spray tank as per claim 2, in which the valve comprises a perforated stop member and a nipple both threaded into the said longitudinal bore, a valve member slidable in the nipple and having a head adapted to 60 seat on the nipple, a spring interposed between the stop member and the valve member, a diaphragm bearing against the valve member and having its faces respectively subject to external air pressure and to the 65 pressure within the said intercepting bore, and spring means engaging the diaphragm on the opposite side from the valve member for resisting a movement of the valve member by the aforesaid spring, the said spring 70 means being adjustable from the exterior of the valve body. 75

Signed at Chicago, Illinois, June 16th, 1922.

HARRY D. BINKS.
